DESIGN FOR A SHOE CLEANING BUFFER

Herbert Daust, St. Louis, Mo.

Application June 3, 1937, Serial No. 69,661

Term of patent 3½ years

To all whom it may concern:

Be it known that I, Herbert Daust, a citizen of the United States, residing at the city of St. Louis, State of Missouri, have invented a new, original, and ornamental Design for a Shoe Cleaning Buffer, of which the following is a specification, reference being made to the accompanying drawing, forming a part thereof, in which Figure 1 is a perspective view and Figure 2 is an end elevational view of a shoe cleaning buffer embodying my new design.

The characteristic features of my design reside

in a buffer of the configuration shown and having a body member of square-shape across its one end and of pointed-shape across its other end with handle-tabs or end-portions each being respectively contoured to symmetrical or matching conformation with the particular adjacent body-end.

I claim:

The ornamental design for a shoe cleaning buffer, substantially as shown and described.

HERBERT DAUST.
